UNITED STATES PATENT OFFICE.

JOHN S. GREENE, OF ROCHESTER, NEW YORK, ASSIGNOR TO COMMERCIAL CAMERA CO., OF PROVIDENCE, RHODE ISLAND, A CORPORATION OF RHODE ISLAND.

PHOTOGRAPHIC DEVELOPING APPARATUS.

1,225,803.

Specification of Letters Patent.

Patented May 15, 1917.

Application filed November 1, 1916. Serial No. 128,889.

To all whom it may concern:

Be it known that I, JOHN S. GREENE, of Rochester, in the county of Monroe and State of New York, have invented certain new and useful Improvements in Photographic Developing Apparatus; and I do hereby declare the following to be a full, clear, and exact description of the same, reference being had to the accompanying drawings, forming a part of this specification, and to the reference-numerals marked thereon.

My present invention relates to photography, and more particularly to copying cameras of the type in which a web of sensitive material is exposed and then immediately developed in the one apparatus, and the invention has for its object to provide a simple and efficient developing attachment for such cameras which will offer certain conveniences to the operator in the matter of handling the print during development and delivering it for withdrawal. The improvements are directed in part toward providing means whereby the excess of liquid developer adhering to the print will be pressed back into the liquid container so that the supply of developer may be conserved and providing for delivery of the print at a point accessible to the operator's fingers in an expeditious and certain manner. To these and other ends the invention consists in certain improvements and combinations of parts, all as will be hereinafter more fully described, the novel features being pointed out in the claims at the end of the specification.

In the drawings:

Figure 1 is a central vertical section through the body of a copying camera, provided with a developing apparatus constructed in accordance with and illustrating one embodiment of my invention;

Fig. 2 is a plan view of the developing pan or container and its attachments;

Fig. 3 is a fragmentary enlarged sectional view through the developing apparatus shown in Fig. 1, but with the parts in different position;

Fig. 4 is a view similar to Fig. 3, but showing the parts in still another position, and Fig. 5 is an enlarged detail view of the parts shown in Fig. 1.

Similar reference numerals in the several figures indicate the same parts.

The whole of the camera or taking part

of the apparatus has not been shown to the extent that the lens and forward parts are omitted, but its general relationship to the developing apparatus will be readily understood from Fig. 1, in which 1 indicates the camera casing or body and 2 the back, which two parts in conjunction with the usual bellows 3 leading from the lens provide an exposure chamber 4. This exposure chamber 4 is arranged forwardly of a film chamber 5 and a chamber 6, the partitions 7 and 8 of which jointly constitute a wall that defines the focal plane of the camera and against which is supported the web 9 of sensitive material in position for exposure. The web is drawn from a supply spool 10 located in the chamber 5 by means of feed rollers 11 and 12 arranged at the bottom of the wall 8 tangent thereto, the said rollers being suitably operated from the exterior of the camera to thrust the print after exposure in the focal plane downwardly through a slot or opening 13 into a pan or fluid container 14 that is filled to about the level shown with developer. The print is then severed by a reciprocating knife 15 driven from the exterior of the camera through the medium of a gear 16 and rack 17, all this mechanism being arranged in the chamber 6 of which the partition 8 constitutes the front wall. A severed print is shown at 19 in Fig. 1 immersed in the developer in the container 14.

The chamber 20 below and extending rearwardly of the camera back 2 is the developing chamber, and to keep this chamber dark it is covered, in the present instance, partly by the camera and partly by a cover 21 that may be hinged at 22 to the back 2 so that it may be raised and access gained to the pan 14. There is another cover portion 23 hinged at 24 to the cover portion 21, and this portion may be independently raised to uncover only a portion of the rear end of the pan for purposes that will herein-after appear. Just in rear of this rear end of the developer container 14 is a receptacle 25 for the hypo or fixing bath, the fluid in which is indicated at 26. The print is drawn out of the developer and immediately immersed in the hypo with one continuous motion, being drawn over a lip 27 provided on the developer pan 14 to overlap the adjacent rim of the hypo container 25.

When the print is fed by the rollers 11

and 12 into the developing chamber 20 through the slot 13 it enters between a curved guide 28 at the forward or receiving end of the pan 14 that directs its advancing edge 5 rearwardly and an adjacent submerging guide or rib 29 that keeps it below the surface of the developing solution. There are a plurality of the guides 28 and 29, as shown in Fig. 2, the latter being carried on transverse bridge pieces 30 spanning the pan. Of course, the rollers 11 and 12 can only partially advance the print into the pan 14 and its rear end is left projecting upwardly in the neighborhood of the slot 13. Additional feeding devices are therefore provided to insure the complete immersion of the print, and in the present instance these comprise parallel shafts 31 and 32 spanning the pan and each provided with rubber or similar 15 yielding paddles 33 that operate between certain of the immersing guides 29. A crank 34 (Fig. 2) accessible on the exterior of the apparatus rotates the shaft 31 and also the shaft 32 in unison therewith by means of a sprocket connection 35. The paddles 33 20 wipe gently against the upper (uncoated) surface of the print and urge it rearwardly until its rear or advancing edge abuts against a stop plate 36 projecting below the immersing guides 29, in which position it is 25 completely immersed, whether it be the longest print that the apparatus is adapted to make or a shorter one. Continued operation of the paddles does not thereafter disturb the print and the paddles additionally act as agitators for keeping the developer in motion so that it flows over the print in currents that insure an even developing action.

When the print is in the position of that shown at 19 in Fig. 1, and has remained there for a sufficient period to be developed, it is removed in the following manner:

The small cover 23 is partially raised, as in Fig. 3. The stop plate 36 is pivoted to this cover at 37 by a knuckle joint, as shown in greater detail in Fig. 5, in connection with a limiting flange 38 on the cover that prevents the stop plate from swinging forwardly. The stop plate is therefore also 40 raised so that it no longer obstructs the progress of the print and rotation of the paddles 33, then moves the latter rearwardly and up the inclined portions 39 of the guides 28, which are at the rear or delivery end of 45 the pan 14, the edge of the print finally projecting over the rims of both of the containers 14 and 25 in a position readily accessible to the fingers of the operator, as shown in Fig. 3. In this position it rests 50 upon a lower fixed wringing member 40 located on the lip 27 and constituted in the present instance by a rounded rib of smooth metal. As the cover 23 is released a co-operating wringing element 41 carried there- 55 by and which may consist of a rubber roller

falls upon the upper surface of the print, where it rests by gravity on the element 40, and as the operator draws the print out of the pan 14 and chamber 20 to immerse it in the hypo 26, the wringers express the surplus developer which flows back into the container 14. It will be seen that this not only conserves the supply of developer, which is desirable but prevents the pollution of the hypo thereby, which is likewise desirable. The co-operating relationship of the wringing element is illustrated in Fig. 4. 70 75

The lower edge of the stop plate 36 is preferably provided with some very loose rollers 42 which prevent any appreciable friction on the print 19. It is also to be noted that the depending plate 36 maintains its vertical position so that it cannot pinch the print against the inclined guide 39, and it furthermore acts as a light guard 80 85 while the cover 23 is raised that prevents a greater portion of the light admitted from reaching back into the developing chamber.

I claim as my invention:

1. In a photographic developing apparatus, the combination with a liquid container adapted to receive sheets of photographic material at one end and having an inclined guide for delivering them out of the container at the opposite end, of means 90 for feeding the sheets up the inclined guide. 95

2. In a photographic developing apparatus, the combination with a liquid container adapted to receive sheets of photographic material at one end and having an inclined guide for delivering them out of the container at the opposite end, of a rotary paddle adapted to act upon the sheets while in the container and advance them up 100 the inclined guide. 105

3. In a photographic developing apparatus, the combination with a liquid container adapted to receive sheets of photographic material at one end and having an inclined guide for delivering them out of the container at the opposite end, of a pair of wringing elements arranged adjacent to the guide and means for feeding the sheets up 110 the latter and between the wringing elements. 115

4. In a photographic developing apparatus, the combination with a liquid container adapted to receive sheets of photographic material and having an inclined guide at one end leading out of the container, of a fixed wringing element adjacent to the guide, a movable wringing element normally co-operating therewith and adapted to be raised by the operator into spaced relationship, and a paddle device for feeding the sheets up the guide and between the wringing elements. 120 125

5. In a photographic developing apparatus, the combination with a liquid container adapted to receive sheets of photo- 130

- graphic material and having an inclined guide at one end leading out of the container, and a displaceable cover for the latter arranged over the guide, of a fixed 5 wringing element adjacent to the guide, a movable wringing element coöperating therewith and carried by the cover and means for feeding a sheet up the guide and between the wringing elements when the 10 cover is raised.
6. In a photographic developing apparatus, the combination with a liquid container having an inclined guide at its delivery end, of a paddle device for feeding photographic sheets through the container toward the guide and for agitating the liquid, and a displaceable stop for preventing the sheets from advancing onto the guide.
7. In a photographic developing apparatus, the combination with a liquid container having an inclined guide at its delivery end and a displaceable cover over the same, of a paddle device for feeding photographic sheets through the container toward the guide and a stop on the cover for preventing the sheets from advancing onto the guide until the cover is raised.
8. In a photographic developing apparatus, the combination with a liquid container having an inclined guide at its delivery end and a displaceable cover over the same, of a paddle device for feeding photographic sheets through the container toward the guide, and a swinging stop plate 35 on the cover for preventing the sheets from advancing onto the guide until the cover is raised.
9. In a photographic developing apparatus, the combination with a fluid container having an inclined guide at its delivery end, 40 and a wringing element adjacent to the guide, of a hinged cover above the latter, a second wringing element carried thereby to coöperate with the first when the cover is down, means for feeding a sheet from the 45 container onto the guide and between the wringing elements when the cover is raised, and a light guard depending from the cover.
10. In a photographic developing apparatus, the combination with a liquid container having an inclined guide at its delivery end and a wringing element adjacent to the guide, of a hinged cover above the latter, a second wringing element carried thereby to coöperate with the first when the 50 cover is down, a paddle device for agitating the fluid and for feeding a sheet of photographic material from the container onto the guide and between the wringing elements when the cover is raised, and a swing- 55 ing plate on the underside of the cover adapted to act as a light guard when the latter is raised and as a stop for preventing the advance of the sheet by the paddle device when the cover is down.
